CLAIM

The ornamental design for a cord organizer, as shown and described.

DESCRIPTION

FIG. 1 is a front perspective view of a cord organizer shown in a closed position;

FIG. 2 is a side perspective view of the cord organizer shown rotated 90 degrees from the orientation shown in FIG. 1;

FIG. 3 is a front elevation view of the cord organizer;

FIG. 4 is a rear elevation view of the cord organizer;

FIG. 5 is a right-side elevation view of the cord organizer;

FIG. 6 is a left-side elevation view of the cord organizer;

FIG. 7 is a top view of the organizer for the cord organizer;

FIG. 8 is a bottom view of the cord organizer;

FIG. 9 is a front perspective view of the cord organizer shown in an opened position; and,

FIG. 10 is a bottom perspective view of the cord organizer shown in an opened position.

The broken lines shown in FIGS. 1, 2, 7, and 9 depict subject matter that forms no part of the claimed design.

1 Claim, 7 Drawing Sheets
